UNITED STATES PATENT OFFICE.

HAROLD W. FORBES, OF GLASTONBURY, CONNECTICUT.

ELECTRIC-WIRE CONNECTOR.

1,006,192.

Specification of Letters Patent. Patented Oct. 17, 1911.

Application filed March 21, 1911. Serial No. 615,828.

To all whom it may concern:

Be it known that I, HAROLD W. FORBES, a citizen of the United States, residing at Glastonbury, in the county of Hartford and 5 State of Connecticut, have invented new and useful Improvements in Electric-Wire Connectors, of which the following is a specification.

This invention relates to improvements 10 in wall brackets for electric lights, and the object of the invention is to provide a device of this character whereby the wires may be easily and quickly fed to the electric lamps.

Another object of the invention is the 15 provision of a device of this class comprising few parts each of which may be separately, and all of which may be easily and adequately connected together.

A still further object of the invention is 20 the provision of a socket employed for directing the wires in opposite directions, the said socket comprising a pair of separable elements and the device being provided with 25 novel means for connecting the socket members with the main chute, and whereby the said socket members are effectively prevented from turning.

With the above, and other objects in view, 30 which will be more apparent as the nature of the invention progresses, the invention resides in the novel construction and combination of parts herein fully described and claimed.

In the accompanying drawings there has 35 been illustrated a simple and preferred embodiment of the invention, and in which drawings—

Figure 1 is a side elevation of a bracket 40 constructed in accordance with the present invention, a part being shown in section. Fig. 2 is a detail elevation, parts being broken away. Fig. 3 is a similar view showing the socket members separated and spread 45 away from the wire conducting tubes.

As illustrated in the accompanying drawings, the canopy employed with the device comprises a pair of sections designated respectively by the numerals 1 and 2. The 50 portion adjacent the wall to which the device is to be attached, and which I will hereafter refer to as the base of the canopy, has its inner face provided with threads, the said threads adapted to coact with similar 55 threads provided upon the globe or canopy proper. The canopy 2 may be of any pre-

ferred or desired formation, and is provided with the usual opening through which the wire conducting pipe 3 projects, it of course being understood that the said tube 3 is extended within the wall of the building in the usual manner and the canopy is secured upon the tube through the medium of a sliding collar provided with a binding or set screw 4. By this arrangement the canopy 60 can be slid upon the tube as desired.

The numeral 8 designates the socket member of the fixture. This socket member is constructed of a pair of separable sections designated respectively by the numerals 9 and 10. The body members of each of the sections are preferably hemispherical and each of the sections is provided with an extending sleeve 11. Each of the said sleeves 11 is semi-circular in cross section and the said 70 sleeves are adapted to snugly engage the extremity of the tube 3. The tube 3 is formed with oppositely arranged pins or projections 12 and each of the sleeves 11 is provided with a suitable opening or recess with 75 in which the said pins 12 are adapted to be received when the socket member is closed and positioned upon the tube. One of the hemispherical body portions of the socket is provided with a tongue 13, and this tongue 80 is adapted to be received within a pocket 14 provided upon the opposite section. The body members 9 and 10 are also provided with oppositely arranged wire conducting pipes 15 and 16.

From the above description, taken in connection with the accompanying drawings, the simplicity of the device, as well as the advantages thereof, will, it is thought, be apparent to those skilled in the art to which 95 said invention appertains. It will be apparent that all of the members comprising the bracket are separable and that the wires may be fed through the openings of the canopy before the tube 3 is inserted within 100 the said canopy. The wires, after being passed through the tube 3 are directed through the oppositely disposed conducting pipes 15 and 16. The socket member 8 being constructed of separable parts readily 105 permits of the feeding of the wires through the said pipes 15 and 16, the sleeves of the socket are positioned upon the tube 3 and the collar 5 is slid over the sleeves 11, thus securing the pins 12 in engagement with the 110 openings or depressions upon the said sleeves. When the collar 5 is properly posi-

tioned, the ring 6 is slid into engagement with the nut of the collar and the ends of the sleeve and its threaded member 7 brought into engagement with the tube 3 to prevent the accidental displacement of the parts.

The device illustrated and described is the preferred embodiment of the improvement as it now appears to me, but it is to be understood that the changes as to size, proportion, shape, etc., within the scope of the appended claims may be made, if desired.

Having thus fully described the said invention, what I claim is:—

- 15 1. A bracket for the purpose set forth, comprising a wire conducting tube, a socket member having conducting pipes for said tube, said socket member comprising a pair 20 of sections, means for securing the sections upon the tube, and means for controlling the rotation of the sockets when upon the tube.
- 25 2. In a bracket for the purpose set forth, a wire conducting tube, a canopy adjustably connected with the said tube, said canopy comprising a base member and a globular member, means for securing the canopy upon the tube, a sectional socket provided 30 with wire conducting pipes connected with the tube, means provided by the tube and the sectional socket for preventing the rotation of the said socket, and means for retaining the socket upon the tube.
- 35 3. In a bracket for the purpose set forth, a wire conducting tube, a sectional socket having wire conducting pipes for the tube, one of the sections of the socket being provided with a tongue, the second section of 40 the socket being provided with a pocket adapted for the reception of said tongue,

means for sustaining the sections of the socket upon the tube, and means for preventing a rotary movement of the socket while positioned upon the tube.

4. In a bracket for the purpose set forth, a wire conducting tube, a socket member for the tube, said socket member comprising a pair of elements, each of said elements having a hemispherical head, each of said elements being provided with a cross sectional semi-circular sleeve, means for connecting the hemispherical heads, oppositely disposed pins upon the tube, the sleeves being provided with recesses adapted to receive 55 said pins, and a sliding member adapted to overlie the sleeves to retain the same upon the tube.

5. In a bracket for the purpose set forth, the combination with a wire conducting tube, 60 a slidable collar upon the tube, a slidable ring provided with a threaded retaining element also upon the tube, a socket for the end of the tube, said socket being formed with heads having extending sleeves, pipe members upon the heads, means for connecting the heads together, pins upon the tube, the sleeves each being provided with a recess adapted to engage one of the pins when the socket is positioned upon the tube, the slid- 65 able collar adapted to engage the sleeves, the ring adapted to contact the inner ends of the sleeves and the inner face of the collar to have its threaded element engage the tube.

In testimony whereof I affix my signature in presence of two witnesses.

HAROLD W. FORBES.
